UNITED STATES PATENT OFFICE.

WILLIAM W. WYER, OF AUGUSTA, MAINE.

SEPARABLE UNION SUIT.

1,073,833.

Specification of Letters Patent. Patented Sept. 23, 1913.

Application filed October 18, 1911. Serial No. 655,402.

To all whom it may concern:

Be it known that I, WILLIAM W. WYER, a citizen of the United States, residing at Augusta, in the county of Kennebec and State of Maine, have invented a new and useful Separable Union Suit, of which the following is a specification.

This invention aims to provide a union garment in which the shirt and the drawers, together with the seat flap, coöperate in a novel manner with a pendent element upon the shirt.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,—Figure 1 is a rear elevation of the invention; Fig. 2 is a longitudinal section through the shirt and the drawers; and Fig. 3 is a longitudinal section through the shirt, the drawers, and the seat flap.

Referring to the drawing, the shirt is denoted by the numeral 100, and the drawers by the numeral 101. The seat flap is denoted by the numeral 102, the same covering the opening 103 in the rear of the drawers, as hereinbefore described. The shirt 100 is surrounded, adjacent its lower end, by a pendent element or band 104, constituting a pendent element which may be a strip of tape. The upper edge of the band 104 is stitched, as shown at 105, to the shirt 100, the lower end of the band 104 hanging free. The upper edge of the drawers 101 is equipped with a row of buttons 106, adapted to be engaged in button-holes 106^a, fashioned in the band 104, adjacent its lower edge, the upper edge of the drawers

101 lying between the band 104 and the shirt 100. The seat flap 102 is equipped with button-holes 108, adapted to be engaged with buttons 107, the buttons 107 passing outwardly through the button-holes 106^a in the band 104. The seat flap 102 is equipped along its edges with button-holes 109, these button-holes 109 being adapted to be engaged with buttons 110 secured to the drawers 101, upon both sides of the opening 103. The lower edge of the shirt 100 is extended below the lower edge of the pendent element 104 to guide the upper edge of the seat flap 102 and the upper edge of the drawers 101 to place. The buttons 107 constitute a means for securing the shirt, the seat flap, the drawers and the pendent element together to prevent the same from rolling up about the waist of the wearer.

Having thus described the invention, what is claimed is:

In a garment of the class described, a shirt; a pendent element secured to the shirt; a pair of drawers having an opening; a seat flap secured to the drawers and constituting a closure for the opening; the upper edge of the drawers and the upper edge of the seat flap being inserted between the pendent element and the shirt, and the lower edge of the shirt being extended below the lower edge of the pendent element to guide the upper edge of the seat flap and the upper edge of the drawers to place; and a single means for securing the shirt, the seat flap, the drawers and the pendent element together, to prevent the same from rolling up about the waist of the wearer.

In testimony that I claim the foregoing as my own, I have hereunto affixed my signature in the presence of two witnesses.

WILLIAM W. WYER.
